[57] **CLAIM**

The ornamental design for ball cock float, as shown and described.

DESCRIPTION

FIG. 1 is a front elevational view of a ball cock float showing my new design;

FIG. 2 is a top plan view thereof;

FIG. 3 is a left side elevational view thereof;

FIG. 4 is a right side elevational view thereof; and

FIG. 5 is a bottom plan view thereof.

The broken line representation of a ball cock in FIG. 1 is for purposes of illustration only.
